[57] CLAIM

The ornamental design for a combined comb and roller, as shown and described.

DESCRIPTION

FIG. 1 is a left side elevational view of a combined comb and roller showing my new design;

FIG. 2 is a bottom plan view thereof;

FIG. 3 is a top plan view thereof;

FIG. 4 is a right side elevational view thereof;

FIG. 5 is an end elevational view thereof, as seen from the left side of FIG. 1;

FIG. 6 is an end elevational view thereof, as seen from the right side of FIG. 1;

FIG. 7 is a side elevational view of a modified embodiment of the design shown in FIGS. 1-6; and

FIG. 8 is a side elevational view of a second modified embodiment of the designs shown in FIGS. 1-6.

FIG. 5

FIG. 1

FIG. 6

FIG. 2

FIG. 3

FIG. 4

FIG. 7

FIG. 8
